UNITED STATES PATENT OFFICE.

WILLIAM LEE, OF GALVESTON, TEXAS.

WINDOW-SHADE-OPERATING LEVER.

1,297,875.

Specification of Letters Patent. Patented Mar. 18, 1919.

Application filed January 7, 1919. Serial No. 270,080.

To all whom it may concern:

Be it known that I, WILLIAM LEE, a citizen of the United States, residing at Galveston, in the county of Galveston and State 5 of Texas, have invented new and useful Improvements in Window-Shade-Operating Levers, of which the following is a specification.

The object of the invention is to provide 10 a simple, relatively inexpensive and efficient means for operating window shades, particularly in the raising and lowering of the same, without involving the necessity of using the spring roller which is now commonly employed and which involves the 15 necessity of manipulating the shade by means of a cord or its equivalent attached to the lower edge of the shade proper, and with these objects in view the invention 20 consists in the construction, combination and arrangement of parts hereinafter fully explained, it being understood that changes in the form, proportion and details may be resorted to within the scope of the appended 25 claim without departing from the spirit of the principles involved.

In the drawing:

Figure 1 is a front view of a shade as applied to a window with its roller mounting 30 and means for operating the same in accordance with the invention.

Fig. 2 is a detail view partly in section of one of the operating means.

Fig. 3 is a side view partly in section of 35 the same.

Figs. 4 and 5 are detail views in perspective of the brackets employed respectively for opposite ends of the shade roller.

Fig. 6 is a detail view of one of the terminal spindles of the shade roller.

The shade 10 is carried by the usual roller 11 having terminal spindles 12 mounted in bearings 13 and 14 formed respectively in the relatively inverted double brackets 15 and 16 supported by suitable bases 17 or the equivalent thereof.

Arranged conveniently within the brackets are the magnets 18 of monocoil motors of which the rotary armatures 19 are secured to the said roller spindles, the latter being held in proper relation to their bearings by bearing disks or washers 20 so as to properly position the armatures with reference to the magnets.

Push buttons 21 and 22 are conveniently

located upon the window casing 23 and are respectively connected by wiring 24 through batteries indicated diagrammatically at 25 with the windings respectively of said magnets so that upon closing one or the other of the switches by actuating a push button, the corresponding magnet is energized to cause rotation of the armature related therewith, and as said armatures and magnets are oppositely positioned at opposite ends of the roll, either a downward or an upward movement of the shade is the result, such movement continuing as long as the circuit is held closed.

Obviously the push button may be arranged upon the same side of the casing instead of at opposite sides thereof as shown, and in either case a convenient operating mechanism is provided in that the shade may be turned either upward or downward 70 to the desired extent without effort upon the part of the operator and without strain upon the shade and also without the risk of disaligning the shade with reference to the window casing as is frequently the result 75 when the movement of the shade is dependent upon strain applied directly to the shade as when the ordinary Hartshorn roller is employed.

It will be noted moreover that the attachment may readily be mounted upon a window casing, all of the parts thereof including the brackets being carried by the common element consisting of the base, and owing to the double or two armed construction of the bracket, a double bearing is provided for each roller spindle, said bearings being arranged as indicated upon either side of the armature so that any tendency to strain in operation is avoided.

Having described the invention I claim:

A shade roller operating mechanism having roller carried spindles, a monocoil motor arranged at each end of said roller, said motors including U-shaped brackets 90 reversely disposed relatively, the magnets of said motors being carried by the cross pieces of the brackets, and the armatures secured to said spindles and operating between the limbs of said brackets, switches in circuit 100 with the windings of said magnets, and a source of electrical energy.

In testimony whereof I affix my signature.

WILLIAM LEE.
